UNITED STATES PATENT OFFICE.

JEREMIAH P. JOHNSON, OF DETROIT, MICHIGAN.

CURTAIN CONSTRUCTION FOR VEHICLES.

1,226,217.

Specification of Letters Patent. Patented May 15, 1917.

Application filed May 16, 1914. Serial No. 338,997.

To all whom it may concern:

Be it known that I, JEREMIAH P. JOHNSON, a citizen of the United States of America, residing at Detroit, in the county of Wayne and State of Michigan, have invented certain new and useful Improvements in Curtain Constructions for Vehicles, of which the following is a specification, reference being had therein to the accompanying drawings.

The invention relates to collapsible canopy tops for vehicles, and it is the object of the invention to provide demountable means for converting such a construction into a closed top. To this end the invention comprises the novel construction of curtain and weather-proofing guides as hereinafter set forth.

In the drawings:

Figure 1 is a diagrammatic side elevation of a vehicle having a canopy top to which my improvement is applied;

Fig. 2 is a perspective view showing one of the bows of the collapsible top together with a curtain guide and a portion of the curtain roll;

Fig. 3 is a cross section through the guide, showing the engagement of the curtains therewith;

Fig. 4 is a perspective view of the curtain and roll detached;

Fig. 5 is a cross section showing the curtain in drawn position; and

Fig. 6 is a section through one end of the curtain roll.

In the present state of the art, vehicle canopy tops have been provided with curtains of various constructions for closing in the sides. Such constructions, while effective in keeping out the rain, do not exclude drafts of cold air, and consequently they are not the equivalent of a permanent closed top. My improvement comprises a construction and arrangement of the curtains in co-operation with weather-proofing guides which effectively exclude the cold air and which are so mounted as to be quickly detachable when it is desired to collapse the top.

In detail, A are weather-proofing guide strips, preferably formed of sheet metal and detachably secured to extend from the sides of the body to the canopy top. These strips may be secured by any suitable means, such as a button B for securing their upper ends,

and flanges C at the lower ends secured to the top rail C' of the body side. Each strip A is formed of two plies of metal A' A'', centrally connected and having their outer edges spaced to form parallel guide slots. 60 The inner ply A'' has the flange C formed as an integral bent portion thereof, while its upper end is slightly flared at A' to form an entering mouth for the curtain. The outer ply A' is provided with a portion D 65 which extends downward and overlaps the side of the body, and at its upper end is provided with a tongue E forming a clip for engaging the curtain roll. F is the curtain roll which is mounted in a holder comprising a bar G extending parallel thereto and having brackets H at its opposite ends for engaging the curtain spindles. The opposite ends of the bar G project beyond the end of the curtain roll to form tongues 75 I for engaging the spring clip E of the guide A, the arrangement being such that the roll and its holder may be quickly engaged or disengaged from the guides by insertion or withdrawal of the tongues I from 80 the clips E. The bar G is also preferably provided with a laterally-projecting flange G', which forms both a reinforcement and a weather-guard for bearing against the canopy top. 85

The curtain J is mounted upon the roll G and is of such a width that its opposite edges may be drawn into the slots of the guide A formed by the parallel plies A' and A''. The overlap is sufficient to produce an 90 effectual weather-proofing joint and to hold the edge from being drawn out of the guide by wind pressure or from any other cause, retainers K are secured at intervals to the curtain and are adapted to engage grooves 95 L in the guides. These retainers may be formed by cords stitched into the curtain and slidable in the grooves of the guides.

With the construction as thus far described, to equip a canopy top with my improved curtains, the guides A are first secured in position by securing the flange C to the body and attaching the upper end of the guide by the button B. The curtain roll with its holder is then placed in position by 105 inserting the tongues I into the clips E, after which the curtain may be drawn downward, its edges engaging the slots in the sides of the guide. If the curtain is completely drawn down, it will extend from the canopy 110

22
top to the side of the body, and preferably will depend slightly below and outside of the upper edge of the side, as shown. At the top, drafts of cold air are excluded by the lateral flange G' on the holder G which bears against the depending portion M of the top and forms a seal.

The curtain may be readily raised or lowered in the guides and in raised position will give full clearance to the door opening of the vehicle. The curtain roll is also concealed by the depending flanges M of the canopy top, while the guides A, being arranged in alinement with the bows N of the canopy top, do not form any obstruction.

My improvement is more particularly designed for use in cold weather and in the summer time may be quickly and easily detached by first disengaging the holder G from the clips of the guides and then detaching and removing said guides.

The retainer K on the edge of the curtain co-operates with inwardly-extending beads K' upon the plies A' A² so as to prevent the lateral withdrawal of the curtain from the guide. This is valuable, first, because it prevents the disengagement or flapping of the curtain under wind pressure, and second, as the beads and retainers form an effectual weather-proofing joint. Where the retainer K is formed as a cord stitched into the edge of the curtain, it might interfere with the smooth rolling of the curtain upon the roller F. This I have avoided by reducing the diameter of the end of the roll, or by extending the edge of the curtain beyond the end, as shown in Fig. 6. The effect of such an arrangement is to permit the increased thickness of the curtain at the edge to be deflected inward instead of interfering with the smooth winding of the curtain thereon.

To weatherproof the joint at the lower edge of the curtain, the latter is provided with a member O, which overlaps the rail of the body and has a hooked lower end O' for engaging a co-operating hook O² on the body. The member O has a finger-grip O³ at its upper end, and for engaging and disengaging the curtain from the inside a corresponding finger-grip O⁴ is arranged on the inside thereof.

What I claim as my invention is:—

55 1. In a top for vehicles, the combination with a canopy top, of grooved vertical guides demountably secured to the bows of said canopy top, a curtain roll frame detachably engaging the upper ends of said guides and having a sealing engagement with the depending flange of the canopy top, a curtain roll mounted in said frame, and a curtain on said roll having its edges

engageable with the grooves of said guides to form a weather seal. 65

2. In a top for vehicles, a grooved guide, a draw curtain having a corded edge for engaging said grooved guide, and a roll on which said curtain is wound cut away at its end to provide clearance for the corded edge. 70

3. In a top for vehicles, vertical grooved guides, a draw curtain having its edges engageable with said guides to form a sealing joint, a roller on which said curtain is wound, and a frame for carrying said roller 75 detachably engaging the upper ends of said guides and having a laterally-extending flange for forming a sealing engagement with the depending flange of the canopy.

4. In a collapsible top for vehicles, a curtain roller, a draw curtain mounted thereupon, vertical guides grooved to receive the curtain edges to form a weather sealed joint therewith, and a bar having a lug at each end for supporting the roller, and a second pair of terminal lugs for detachably engaging the bar with said guides. 80

5. In a top for vehicles, a roller, a draw curtain mounted thereupon, a non-revolvable frame supporting the roller, and vertical guides formed at their upper ends to engage lugs projecting endwise from said frame and grooved to receive the curtain edges to form a weather sealed joint therewith. 90

6. In a top for vehicles, a curtain roller, a draw curtain mounted thereupon, and vertical guides having at their upper ends tongues forming clips to engage the curtain roller and grooved to receive the curtain edges to form a weather sealed joint therewith. 100

7. In a top for vehicles, a curtain roller, a draw curtain mounted thereupon, a frame having two terminal lugs at each end, one for supporting the roller and the other for supporting said frame, and vertical guides, the upper ends of which are detachably engaged by said frame supporting lugs, said frame having a laterally projecting flange for forming a sealing engagement with the depending flange of the canopy top. 110

8. In a top for vehicles having a depending canopy flange, a draw-curtain, a roller on which said curtain is wound, and a frame for supporting said roller in a spaced relation to the inner face of said depending flange, said frame being formed with a laterally-extending flange for forming a sealing engagement with the depending flange of the canopy. 115

In testimony whereof I affix my signature 120
in presence of two witnesses.

JEREMIAH P. JOHNSON.
